UNITED STATES PATENT OFFICE.

JOHN COYLE, OF BALTIMORE, MARYLAND, ASSIGNOR TO CONTINENTAL CAN COMPANY, INC., OF SYRACUSE, NEW YORK, A CORPORATION OF NEW YORK.

TIMING DEVICE FOR CAN MACHINES.

Application filed January 14, 1921. Serial No. 437,214.

To all whom it may concern:

Be it known that I, JOHN COYLE, a citizen of the United States, residing at the city of Baltimore, in the State of Maryland, have 5 invented certain new and useful Improvements in Timing Devices for Can Machines, of which the following is a description, reference being had to the accompanying drawing and to the figures of reference 10 marked thereon.

The invention relates to new and useful improvements in timing devices for receiving cans fed promiscuously thereto and for delivering the cans at predetermined timed intervals, to a machine operating thereon, and more particularly to a timing device adapted to receive filled cans and deliver the same to a closing machine or an assembling mechanism which applies the covers thereto 15 and in return delivers the cans with the applied covers to the closing machine.

An object of the invention is to provide a timing device having movable members for feeding and timing the cans and devices 25 associated therewith and engaging the cans at substantially opposite sides thereof for moving the same laterally into the timed position relative to said movable timing members.

30 A further object of the invention is to provide a timing device of the above character, wherein the cans are timed by a moving member having pockets arranged therein at predetermined distances apart and 35 wherein means is associated with said member for closing and opening the pockets, so as to restrain the can from too sudden movement as it is caused to enter the pocket.

40 A still further object of the invention is to provide a timing device of the above character with yielding means adapted to engage the can at the opposite side from the pocket for yieldingly moving the can laterally into the pocket as it opens.

45 A further object of the invention is to provide a timing device of the above character with an overflowing pad, and means for operating the same, so as to cause the pad to move into and out of the can to overflow the same during its bodily travel.

These and other objects will in part be obvious and will in part be hereinafter more fully disclosed.

In the drawings which show by way of

illustration one embodiment of the invention— 55

Figure 1 is a plan view showing a timing device embodying my improvements;

Figure 2 is a vertical sectional view on the line 2—2 of Figure 1; 60

Figure 3 is a vertical sectional view on the line 3—3 of Figure 1;

Figure 4 is a vertical sectional view on the line 4—4 of Figure 1;

Figure 5 is a vertical sectional view 65 through the timing device adjacent one of the radial ribs which assists in positively delivering the cans to the rotating assembling means;

Figure 6 is a sectional view on the line 70 6—6 of Figure 1;

Figure 7 is a perspective view of the supporting bracket for the controlling arm which permits the feed of the covers;

Figure 8 is a perspective view of the 75 bracket at the receiving end which carries the support for the gravity controlled fingers;

Figure 9 is a sectional view on the line 9—9 of Figure 3; 80

Figure 10 is a sectional view on the line 10—10 of Figure 3;

Figure 11 is a plan view of the main housing for the timing device; and

Figure 12 is a sectional view on the line 85 12—12 of Figure 11.

The invention consists broadly in a timing device for receiving filled cans promiscuously either from a filling machine or any source of supply, and this timing device 90 feeds the cans forward and at the same time moves them laterally and retards or advances the cans so as to place them in pockets or against timed devices. Associated with the member having the pockets 95 for timing the cans is means which in effect closes and opens the pockets in succession and in proper timing so that a filled can when presented to one of the pockets is held from sudden movement into the pocket and 100 is caused to gradually enter the pocket as it opens. Associated with said timing element and the controlling means for retarding the entrance of the can into the pocket are yielding devices which engage the can 105 on the opposite side from the controlling means associated with each pocket and these yielding devices force the can into the pocket

2
as it opens, moving the same laterally and slightly advancing or retarding the can as it may be necessary to have it fully entered and centered in the pocket. The means 5 which closes the pocket also operates to positively move the can out of the pocket at a proper time, and devices are associated with the timing device for delivering the cans on to an assembling turret where the 10 cover is applied and the assembling turret delivers the filled cans and applied covers to a closing machine.

Also associated with the timing mechanism is an overflowing mechanism which includes a reciprocating pad which moves in more or less of an elliptical path so as to travel with the can and move into and out of the mouth of the can during its bodily travel for overflowing the same. This occurs 15 while the can is in the pocket of the timing mechanism. The above mechanism co-operates to receive the cans promiscuously, time the cans and deliver them to the assembling turret, and permits inspection 20 of the cans while they are being timed; also overflows the can so that each can will contain the exact or desired amount of syrup.

Referring more in detail to the drawings, my improved timing device consists of a rotating table 1, on which the cans are delivered 30 from a rotating disk 2, and the rotating disk 2 receives the cans from the filling machine or other source of supply. The cans are delivered from the rotating table 35 1 on to an assembling turret 3. This assembling turret is of the construction shown in the patent granted to A. L. Kronquest and John C. Taliaferro, August 3, 1920, No. 1,348,650, and has been shown only in a 40 fragmentary way in the drawings.

The turret has a series of half molds or segmental pockets 4 which receive the filled cans and deliver the same to the closing machine.

45 The rotating table 1 is preferably operated from a connection with the rotating turret and this rotating turret is in turn operated from a connection with the main closing machine, as fully set forth in the 50 patent referred to. On the rotating turret is a beveled gear wheel 5 and this beveled gear wheel 5 meshes with a beveled gear wheel 6 on a shaft 7 which shaft 7 is journaled in the main housing 8 of the timing device.

55 Adjacent the inner end of the shaft 7 is a beveled gear wheel 9 and this beveled gear wheel 9 meshes with a beveled gear wheel 10 which is secured to the table 1 by bolts 11—11, see Figure 2. As the shaft 7 rotates, the table 1 will be rotated thereby. Secured to this rotating table is the timing member 12. This timing member is provided with a series of segmental pockets 13 which are curved to conform substantially 60 to the curvature of the cans being timed.

As shown in the drawings, the member 12 is provided with five segmental pockets. It will be understood that the number of pockets may be increased or decreased, according to the size of cans being operated upon. The essential feature resides in the member 12 operating to space the cans a pre-determined distance apart.

One of the particular features of the invention consists in the means for seating 75 the cans in the segmental pockets. It is understood that this machine is particularly adapted for receiving and delivering filled cans and the cans are fed on to the rotating table 1 and will be continuously fed in a 80 curved path about the center of rotation of said table moving with the table. In order to properly seat the cans in the segmental pockets, they must be moved laterally of their forward path of travel and it is to accomplish this lateral movement of the cans without any sudden or jerking movement thereof that the following mechanism is provided:

Said mechanism consists broadly in means 90 for, in effect, closing the pockets to the entrance of the can, which means gradually opens the pockets so as to restrain the lateral movement of the can as it enters the pocket and permit it to gradually enter the 95 pocket without any sudden or jerking movement thereof. As a compelling force to move the can laterally, I have provided yielding gravity fingers which engage the cans in their path of travel and produce a 100 yielding lateral force against the can which will cause it to enter the pocket as it opens.

My preferred means for closing and opening the pockets consists of a rotating member 14 which is shaped similarly to the timing member 12. This rotating member, therefore, is provided with a series of segmental pockets 15 which conform in shape to the pockets 13 on the timing member 12. As shown in the drawings, there are six 110 segmental pockets 15. If the number of pockets in the timing member 12 be increased, then the number of pockets in the rotating member 15 will be likewise increased, so that there is one more pocket in 115 this controlling rotating member 15 than there is in the timing member 12. The member 14 is caused to rotate at differential speed relative to the member 12. On the main shaft 7 is a beveled gear wheel 16 120 which meshes with a beveled gear wheel 17 connected to a sleeve 18, extending centrally through the member 12. Rigidly secured to this rotating sleeve is the member 14. The gear wheels 9 and 16 both rotate, of course, in timing with the shaft 7, as they are rigidly attached thereto. These gear wheels, however, are of different diameters and will, therefore, produce a differential movement in the gear wheels 17 and 10, which are also 125

of different diameters. This differential movement is preferably such that the arm 19, for example, on the member 14 is midway between the arms 20 and 21 between adjacent segmental pockets 13 in the member 12 when the segmental pocket 13 is approaching the point where the can will enter the pocket. The table 1 and the timing member 12 move as one and as the can moves forward this arm 19 moves slower than the arm 21 and thus gradually opens the pocket, so that the can may be caused to enter the pocket when the point is reached, indicated at A, then the two pockets in the members 12 and 14 are substantially in register, and, therefore, the can may be fully seated in the pocket in the timing member 13. When the can reaches the position indicated at b, then the arm 19' will fall behind the adjacent arm on the member 12 and will positively force the can out of the segmental pocket. The member 14 travels slower than the member 12 and this brings about the timing of the parts, above described.

Associated with the timing device, as above noted, are the gravity fingers. Each of these gravity fingers consists of a can engaging part 22, which is formed with a rounded end 23. The can engaging part 22 is carried by a body portion 24, which consists of spaced arms 25—25, connected by a member 26. The arms 25—25 are inclined toward each other and form a curved fulcrumed seat 27, which rests upon a bar 28, similarly curved at its upper edge. Projecting downwardly from one of the arms 25 is a rod 29, and on this rod is a weight 30, which is shown in the drawings as disk shape. The weight is secured in adjusted positions on the arm 29 by means of a set screw 31.

It is understood that there are a series of these can engaging fingers 22 and the inner ends thereof are arranged in a curve concentric with the center of rotation of the table 1. The fingers also extend from the point adjacent where the can is received on the rotating table and terminate at a point where the cans are fully nested or seated in the segmental parts. These gravity fingers, as above noted, are carried by a supporting rail 28, which, of course, is curved to conform to the position of the fingers. Said rail is carried by a bracket 32 adjacent the receiving portion of the timing device and a bracket 33 adjacent the other end of the row of gravity fingers. These two brackets 32 and 33 are bolted to the main housing 8. There is a cover plate 34 also carried by these brackets 32 and 33, which in part houses the gravity fingers.

The filled cans are delivered, as above noted, from the disk 2 on to the rotating table 1 and curved guiding rails 35 and 36 are provided for directing the movement

of the cans, so that they will be brought into engagement with the gravity fingers and by said gravity fingers forced laterally into contact with the arms between the segmental pockets in the timing member 12 and the controlling member 14. These arms will be slightly spaced when the cans come into contact therewith and by reason of the fact that the controlling member 14 is moving slower than the table and the timing member, the two arms gradually separate and permit the can to move into the segmental pocket 13. The fingers are stationary, so far as the travel of the can is concerned, so that the can moves along these gravity fingers, which produces a continuous lateral yielding force against the can which operates to enter the can in the pocket as the pocket opens. It will thus be seen that the can is controlled at both sides, on one side by the controlling arm of the member 14 and the arm between the segmental pockets 13 and at the other side by the gravity fingers, and this constitutes means which controls the can as it moves laterally and prevents any sudden or jerking movement of the can as it is seated in the segmental pockets. Furthermore, the gravity fingers more or less retard the forward movement of the cans and holds the same against the controlling arm of the member 14, and causes the can to move into the pocket.

I have shown the last two gravity fingers as provided with a guiding rail 37 which yields with the gravity fingers but which serves to hold the can seated in its segmental pocket as it moves along with the table for a brief period of time. It is during this interval, while the can is fully seated in the segmental pocket, that the overflowing of the can is accomplished. As shown in the drawings, I have provided an overflowing pad 38. This pad is carried by an arm 39 which is secured to a rod 40 extending centrally through a sleeve 41, which is fixed to the housing 8. This rod is raised and lowered and is adjusted during its movements up and down, and these movements up and down, together with the oscillating movements, cause the pad to move in a curved path which is of such a character that the pad enters the open mouth of the can body and causes an overflow of the syrup in the can, if it is too full, travels with the can while it is in the mouth thereof and is then moved out of the mouth and returned so as to operate in conjunction with the next can. The rod is raised and lowered by means of a crank 42. This crank 42 is carried by a shaft 43, mounted in suitable bearings in the housing 8. Rigid on the shaft 43 is a gear wheel 44, which meshes with a gear wheel 45 on the shaft 7. Pivoted secured to the crank 42 is a cross head 45. This cross head at its lower end is pivotally

mounted upon a rod 46, carried by a sleeve 47, which in turn is mounted on the rod 40 between fixed collars 48-48 secured to the rod. At the outer end of the rod 46 there is a roller 49, which runs between parallel guides 50-50. As the crank rotates this cross head 45 will be moved up and down vertically and will reciprocate the rod 40. The sleeve 47 is freely connected to the rod 10 and the cross head is guided by the reciprocating movements of the rod and the guides 50-50. As the cross head 45 goes up and down it will move laterally about the rod 46 as a pivot point. Extending from the rod 15 40 is a U-shaped arm 51. Said arm is clamped to the rod by means of a bolt 52. At the outer end of the members on the U-shaped arm are rollers 53-53, see Figure 9, and these rollers engage the circular web 20 of the cross head 45. As the cross head oscillates at the point of engagement of the rollers 53-53 therewith, the U-shaped arm will be vibrated, and this in turn will oscillate the rod 40. From the above, therefore, 25 it will be apparent that the crank 42 performs the double function of raising and lowering the pad and causing the pad to travel with the can while in the mouth of the can.

30 A guide rail 54 is mounted at one end upon a projecting arm 55, attached to the fixed sleeve 41, and at the other end upon a part of the frame of the turret. This guide rail is curved so as to direct the path of movement of the cans from the pockets of the timing device into the pockets of the turret and operates in the usual well known manner. There is a guide rail 56 mounted upon the upper end of a vertical shaft 57, which 35 engages the outer faces of the cans and the can bodies pressing against this rail 56 will swing the shaft 57 a limited distance. The shaft 57 is mounted in bearing sleeves 58, carried by the bracket 33. At the lower end 40 of this shaft, there is an arm 59, see Figure 1, which is pivotally connected to a link 60, and the link 60 is in turn pivotally connected to a rock arm 61 associated with the assembling turret and operating to release a can 45 end, so that the can ends are only released as a filled can passes this guiding rail 56. This is the well known no can no end controlling means, and may be similar to that shown in the patent above referred to. A 50 spring 62 is associated with the rock arm 61 and yieldingly holds the guide rail 56 in contact with the cans.

I may also use, if desired, a series of radial ribs 63. These ribs, as more clearly shown 60 in Figure 5, are mounted in recesses 64, and each rib carries a stem 65, which projects downwardly from a supporting sleeve 66, and the lower end of the stem is rounded, as indicated at 67.

Attached to the housing 8 is a cam rail 68. 65 This cam rail is stationary and may be adjusted vertically by means of slots 69 through which the bolts pass for securing the cam rail to the housing. At the receiving end of the cam rail there is a cam ledge 70 69'. As the turret rotates these radial ribs will be raised when the rounded end 67 comes into contact with the cam ledge 69'. There is a rib for each segmental pocket, and the ribs are so associated with the pockets as to 75 engage in rear of the cans and positively hold them in a predetermined position on the rotating table, so that they will be properly delivered into the pockets, in the well known manner.

80 Rigidly secured to the guide rail 54 is a depending arm 70, which carries a roller 71, and this roller 71 insures that the radial ribs will be again seated in the recesses 64 therefore when the rounded ends of the stems carried by the radial ribs pass off from the cam ledge and this occurs at just about the time when the can is placed in the segmental pocket in the turret, the cam rail being 85 shown in dotted lines in Figure 1.

90 In the operation of my machine, the filled cans are fed on to the rotating table from a rotating disk, guiding rails operate to direct the movements of the cans. As the cans come into contact with the gravity fingers, 95 they also come into contact with an arm between the segmental pockets in the timing device and an arm in the segmental pockets in the controlling member, and, as the controlling member moves slower than the timing device, these arms gradually separate, thus opening the pocket for the can to enter and the distance between the ends of the arms and the gravity fingers is less than the 100 diameter of a can, so that the gravity fingers are moved back and thus operate to yieldingly force the can against these arms and also retard the can, so that it will be held against both arms, and, as the arms 105 separate, it will gradually enter the pocket and when fully seated in the pocket, it is timed and will be carried forward for an interval through the rotating of the pocket and the table and at this interval the over-flowing pad operates to perform its function, 110 after which the filled can is gradually and positively moved out of the pocket through the aid of the advanced arm between the segmental pockets in the controlling member 115 approaching the rear arm of the segmental pocket containing the can. By adjusting the weights on the rods connected with the gravity fingers, the yielding pressure may be varied. This pressure is not great, but just sufficient to hold the can in contact with the arms, as stated above, and to insure that the can will move into the pocket as the pocket 120 opens.

It will be apparent from the above description that I have a double control on the can, so to speak. In other words, the co-operating arms engage the can at one side and the yielding gravity fingers engage the can at the other side; and, while the yielding fingers are at all times yieldingly forcing the can laterally, the controlling arms are resisting its movement, but gradually opening the pocket to permit the can to enter, and thus a very even smooth movement of the can is obtained during the lateral shifting and retarding of the can to seat it in the timing pocket.

15 It is obvious that other devices than those herein shown may be used for transferring the can from the timing pocket to the turret, the present structure merely illustrating one way of accomplishing this transfer.

20 It is obvious that minor changes in the details of construction and arrangement of the parts may be made without departing from the spirit of the invention as set forth in the appended claims.

25 Having thus described my invention, what I claim as new and desire to secure by Letters Patent, is:

1. A timing device for filled cans including in combination, a continuously moving timing element having spaced arms forming pockets therebetween, stationary yielding means for forcing the cans laterally in succession into said pockets, and movable means associated with the timing element for engaging the cans and gradually restraining the entrance of the cans into said pockets.

2. A timing device including in combination, a rotating timing element having spaced arms forming therebetween a series of pockets, yielding means associated with said timing element for forcing the cans laterally into said pockets, and rotating means movable about the same center as the timing element and at a different speed relative to said timing element for engaging a can and gradually restraining the entrance of the can into the pocket.

3. A timing device for cans including in combination, a continuously moving timing element having a series of spaced arms forming pockets therebetween, travelling means associated with said timing element and engaging the cans in succession for gradually permitting the entrance thereof into their respective pockets, and yielding means operating upon the cans in succession for laterally moving the cans into the pockets.

4. A timing device for cans including in combination, a continuously moving timing element having spaced arms forming a pocket therebetween, means associated with said timing element for engaging a can and gradually permitting its entrance into said pocket, and yielding means for forcing the

can laterally into said pocket, said yielding means including a plurality of gravity operated fingers.

5. A timing device for cans including in combination, a continuously moving timing element having spaced arms forming a pocket therebetween, means associated with said timing element for engaging a can and gradually permitting its entrance into said pocket, yielding means for forcing the can laterally into said pocket, said yielding means including a plurality of pivoted members having rounded fingers for engaging the cans, and an adjustable weight carried by each member for forcing the fingers yieldingly into the path of travel of the cans.

6. A timing device for cans including in combination, a continuously rotating timing element having a plurality of equally spaced fingers forming pockets therebetween, a continuously rotating controlling element associated with said timing element for engaging the cans in succession and gradually permitting the entrance of the cans into the pockets, and yielding means curved to conform to the path of travel of the cans for forcing the cans laterally into said pockets as they move forward.

7. A timing device for cans including in combination, a rotating table, a timing element carried thereby, and having a plurality of equally spaced arms forming pockets therebetween shaped to conform to the curvature of the cans, a controlling element associated with said timing element and moving at a differential speed relative thereto for engaging the cans in succession and gradually permitting their entrance into the respective pockets, and yielding means for forcing the cans laterally into the pockets during their forward travel.

8. A timing device for cans including in combination, a rotating table, a timing element carried thereby, and having a plurality of equally spaced arms forming pockets therebetween shaped to conform to the curvature of the cans, a controlling element associated with said timing element and moving at a differential speed relative thereto for engaging the cans in succession and gradually permitting their entrance into the respective pockets, a plurality of yielding gravity fingers for engaging the cans and forcing the same laterally into said pockets, said fingers being mounted so as to move laterally of the path of travel of the can only.

9. A timing device for cans including in combination, a rotating table, a continuously moving timing element secured to the table and having a series of equally spaced arms with curved pockets therebetween corresponding substantially to the curvature of

the can bodies, a similarly shaped controlling element mounted to rotate about the same axis as said timing element and moving at a differential speed relative thereto, 5 said element being so timed as to engage the cans and gradually permit their entrance into the pockets, and yielding means for forcing the can laterally into contact with said rotating element and into the 10 pockets.

10. A timing device for cans including in combination, a continuously moving timing element having spaced arms forming a pocket therebetween, means associated with 15 said timing element for engaging a can and gradually permitting its entrance into said pocket, yielding means for forcing the can laterally into said pocket, an overflowing pad and means for supporting and operating said pad, whereby it is caused to enter the mouth of the can during the forward travel thereof and after said can has been seated in the pocket therefor.

11. A timing device for cans including in 25 combination, a rotating timing element having a series of equally spaced arms forming pockets therebetween, a second rotating element similar in shape to the timing element and mounted to rotate about the same axis, 30 means for driving said second element at a differential speed relative to the timing element, whereby the arms on said second element will permit the gradual entrance of the cans into the pockets of the timing element, 35 and yielding means located in the path of travel of the cans for forcing the same laterally into their respective pockets.

12. A timing device for cans including in 40 combination, a rotating timing element having a series of equally spaced arms forming pockets therebetween, a second rotating element similar in shape to the timing element and mounted to rotate about the same axis, 45 means for driving said second element at a differential speed relative to the timing element, whereby the arms on said second element will permit the gradual entrance of the cans into the pockets of the timing element, yielding means located in the path of travel 50 of the cans for forcing the same laterally into their respective pockets, an overflowing pad positioned so as to engage within the can when seated in the pocket, and means for

moving said pad up and down and laterally, so that said pad travels with the can while 55 moving into and out of the same.

13. A timing device for cans including in combination, a rotating timing element having a plurality of equally spaced segmental pockets, a controlling element associated therewith and similarly shaped to said timing element, means for rotating said controlling element at a differential speed, said element being timed so as to gradually permit the cans to enter the pockets, a rotating 60 table for supporting the cans, and a plurality of pivoted fingers movable laterally of the path of travel of the can only for forcing the cans laterally into said pockets.

14. A timing device for cans including in 70 combination, a rotating timing element having a plurality of equally spaced segmental pockets, a controlling element associated therewith and similarly shaped to said timing element, means for rotating said controlling element at a differential speed, said element being timed so as to gradually permit the cans to enter the pockets, a rotating table for supporting the cans, a plurality of pivoted fingers movable laterally of the path 75 of travel of the can only for forcing the cans laterally into said pockets, an overflowing pad, means for supporting and operating said overflowing pad, whereby the same moves into and out of the can and with the 80 can during its bodily travel.

15. A timing device for cans including a rotating table, a timing element secured to the table and rotating therewith, said timing element having a series of equally spaced and similarly shaped timing pockets, a similarly shaped controlling element mounted to rotate about the axis of the table, means for rotating said controlling element at a differential speed relative to the speed of the table, whereby the pockets are opened and closed to permit the entrance of the cans and to eject them from the pockets after they are timed, yielding means for forcing the cans laterally on the rotating table into the pockets, guiding rails for directing the cans from the pockets, and guiding rails for directing the cans from the source of supply on to the rotating table.

In testimony whereof, I affix my signature.
JOHN COYLE.
